UNITED STATES PATENT OFFICE

132,980

DESIGN FOR A MAGNIFYING PAPERWEIGHT

Alfred Robbins, New York, N. Y.

Application April 11, 1942, Serial No. 106,555

Term of patent 14 years

To all whom it may concern:

Be it known that I, Alfred Robbins, a citizen of the United States and resident of the Borough of Manhattan, city, county, and State of New York, have invented a new, original, and ornamental Design for a Magnifying Paperweight, of which the following is a specification, reference being had to the accompanying drawing, forming a part thereof.

Fig. 1 is a top plan view of a magnifying paperweight embodying my new design;

Fig. 2 is a side elevation thereof;

Fig. 3 is a bottom plan view thereof; and
Fig. 4 is a section taken in the plane of the line IV—IV of Fig. 3 looking in the direction of the arrows.

The dominant features of my new design are shown in solid lines on the drawing.

I claim:

The ornamental design for a magnifying paperweight, substantially as shown and described.

ALFRED ROBBINS.
